Specification of Letters Patent. Patented Mar. 14, 1922.

Application filed July 7, 1908, Serial No. 442,288. Renewed October 27, 1917. Serial No. 198,880.

To all whom it may concern:

Be it known that I, CHARLES F. STODDARD, a citizen of the United States, and a resident of Boston, in the county of Suffolk and Commonwealth of Massachusetts, have invented an Improvement in Piano Players, of which the following description, in connection with the accompanying drawings, is a specification, like letters on the drawings 10 representing like parts.

This invention relates to automatic means for playing musical instruments such as pianos; and pertains more particularly to means for governing tone intensities.

Among other objects, the invention may provide apparatus capable of governing the energy used for sounding a tone or tones, as for striking the strings of a piano; and the invention contemplates simple and 20 stable, though accurate and effective, means to this end.

For illustration, the accompanying drawings show one practicable embodiment of the invention employing suitable pneumatically 25 governed devices in coöperation with a piano action; but, as will appear to those skilled in the art, the invention is susceptible of embodiment in various constructions and organizations other than that particularly 30 shown and described herein.

In the drawings,—

Fig. 1 is a diagrammatic representation of a typical piano action with operating and governing means embodying the invention; 35 and

Fig. 2 represents a practicable form of music sheet which may be employed to control the apparatus shown in Fig. 1.

Referring now to Fig. 1, a typical key action is shown in its normal position of rest. 40 When the key A is struck it elevates a sticker B, rocking a hammer C and causing the latter to strike a string D, at the same time withdrawing from the string a damper E. This same operation may be effected automatically as well understood in the art,—as 45 by means of a motor pneumatic F, suitably controlled from a tracker board G as presently described, which acts through the medium of a sticker H to elevate a rocker I controlling the hammer C.

Associated with the key pneumatic F are a primary chamber 5 and a secondary chamber 6, each communicating with a trunk 7 containing air preferably under tension. 55 The chamber 5 communicates by a suitable duct with a diaphragm chamber under a valve 8 which controls a second duct between the chamber 6 and the interior of the pneumatic F. A valve 9 controls a port of the 60 chamber 5; and, in turn, is controlled by a diaphragm, to the under face of which atmospheric pressure is admitted through a conduit 10 leading to a vent in the tracker board G. The operation of these parts is 65 such that opening of the tracker board vent of the conduit 10 lifts the valve 9; which admits atmospheric pressure beneath the diaphragm controlling valve 8. This shuts off atmospheric pressure from the pneumatic 70 F by said valve 8; and opens communication between the chamber 6 which is the usual exhaust chamber and the pneumatic, whereby the latter is collapsed and caused to operate the hammer action through the 75 sticker H.

The preceding description is merely explanatory of one form of tone producing means which may be used in practising the invention. In the preferred embodiment 80 illustrated in the drawings the intensity with which the string D is struck, is determined by governing the tension in the chamber 6, which acts upon the motor pneumatic F. 85

The trunk 7, which may communicate with all of the key actions collectively, is also in communication with a chest 12, in which the tension may be regulated by means presently to be described. There is 90 also provided a high tension chest 14 in which the tension may be maintained in any desired degree, as by means of feed bellows 15, 15 actuated in any suitable manner, as by having their boards connected by links 16 95 with a crank shaft 17, driven through a worm and gear by a motor 18. One of the bellows 15 is sufficiently broken away to show communication from the interior thereof to the high tension chest 14 with a flap 100 valve 19.

It is preferred to maintain a substantially

- uniform tension in the chest 14, and this may be done by a governing pneumatic 21 having a port 22 connecting the interior of the pneumatic with the high tension chest 14.
- 5 Within the pneumatic is a governing spring 23 which tends to distend the pneumatic and balance the effect thereupon of the tension in the chest 14. A flap valve 24 on the pneumatic 21 has a preferably adjustable stop device 25 such that when excessive tension in the chest 14 collapses the pneumatic beyond a certain point (against the spring 23) the stop device, abutting against the top board of the pneumatic, will open 10 the valve 24 so as to reduce the tension,—the effect being to govern the tension and maintain it substantially uniform.
- Between the high tension chest 14 and the regulated tension chest 12 is a chamber 30, 20 having ports communicating with said chests respectively. One set of said ports (for example, those communicating with the high tension chest 14) is provided with a piston valve 31, by which communication between 25 the two chests may be governed so as to subject the regulated tension more or less to the effect of the high tension.
- The stem 32 of the valve 31 is preferably connected to the latter by parti-spherical 30 nuts threading on said stem at opposite sides of the face of the valve, thereby permitting the latter to adjust itself readily to the chamber 30 and slide freely therein. The stem 32 projects upwardly with a close 35 though sliding fit, through the top wall of the chamber 30 and into a series of cylinders where it is connected to pistons 34, 35 and 36. Preferably this tier of pistons is embraced on opposite sides by parti-spherical 40 nuts 33, 33 threading on the valve stem 32; and adjacent pistons may be separated by flanged collars 37 and 38, all of which are preferably so assembled as to permit the pistons to adjust themselves readily to their 45 cylinders without danger of binding.
- The valve 31, the pistons 34, 35 and 36, and other parts connected thereto, are preferred to be of light construction—as by being made of aluminum—so as to have 50 minimum inertia in the operation of the devices as presently described. Also it is preferred that the piston structure be unrestrained by mechanical means, so that it may be balanced, or otherwise completely controlled, pneumatically, as by being suspended pneumatically.
- 55 A duct 40, communicates with the cylinder above the piston 36. A duct 41 communicates with the cylinder between the pistons 35 and 36; and a duct 42 communicates with the cylinder between the pistons 34 and 35. Beneath the piston 34 the cylinder is preferably open to atmospheric pressure through one or more ports 43.
- 60 As hereinafter described, the ducts 40, 41 and 42 are so controlled as to communicate to their respective cylinders either atmospheric pressure, or regulated tension from the chest 12. As illustrated in Fig. 1 the cylinder between pistons 34 and 35 and that above piston 36 are open to atmosphere, while the cylinder between pistons 35 and 36 is in communication with the regulated tension chest 12. Accordingly, the tension between pistons 35 and 36 is the same as that in the regulated tension chest 12; and this same tension is present at the upper side of the piston valve 31 in the chamber 30. The tension at the under side of the piston valve 31 is that prevailing in the high tension chest 14, which is preferably constant.
- 65 Under the specific conditions described, different tensions involved control the collective piston structure with the result about to be explained.
- 70 As illustrated, the piston 36 is of less area than the piston 35, and the latter is of less area than the piston 34. The regulated tension between the pistons 35 and 36 exerts a downward pull on the latter and an upward 75 pull on the former, the resultant pull being proportioned to the differential between the two piston areas. In the specific instance cited this resultant is an upward pull on the valve stem 32, which is augmented by the 80 pull of regulated tension in the chamber 30 on the upper face of the piston valve 31.
- 85 Opposing these collective upward pulls, the preferably constant high tension in chest 14 exerts a downward pull on the piston 100 valve 31. Thus the high tension acts downwardly on the area of the piston valve 31; while the regulated tension acts upwardly upon the same area and, in addition, upon the differential of the areas of pistons 35 and 36. The greater piston area is therefore 95 favorable to an upward pull; and an upward movement will result unless there exist an inverse proportion between the opposed piston areas and the regulated and high tensions. Whenever such proportion prevails, 110 however, the collective piston structure may be held in balance without movement.
- 115 If from any cause the balance be destroyed so that an upward movement results, the piston valve 31 will be elevated to restrict the openings between the high tension chest 14 and the chamber 30, thereby reducing the flow of air between the chests 14 and 12, and thus reducing the regulated tension in the 120 latter. The regulated tension being a component factor in the prevailing upward pull, the described reduction in said tension diminishes the upward pull until the balancing proportion is restored, whereupon the piston structure may be balanced and come to rest.
- 125 If on the other hand, the balance be destroyed so that a downward movement results, the piston valve 31 will be depressed, 130

so as to enlarge the opening between the chests 12 and 14, increasing the flow of air therebetween and increasing the regulated tension. Such increase will continue until the balancing proportion is restored, whereupon the piston structure may again come to rest.

It will appear from the above explanation that there is a constant tendency upon the 10 part of the piston structure to maintain a position such that the balancing proportion shall always prevail. For the purposes of this discussion (but without essentially limiting the invention thereto) it may be assumed that two of the factors involved in this proportion are constant, to wit: the high tension, and the piston valve area acted upon by high tension. The other factors may be considered variables, to wit: the piston areas acted 20 upon by regulated tension, and the regulated tension itself. As hereinafter described, said piston area factor may be varied according to any practicable method of control (as by a perforated sheet) and may govern 25 the balancing proportion so as to determine the regulated pressure.

For example, if regulated tension be admitted between pistons 34 and 35 in addition to between pistons 35 and 36, the effect of the 30 same on opposite sides of piston 35 will balance and the resultant will be proportioned to the differential of the areas of pistons 34 and 36, this differential being in the specific construction considerably greater 35 than that heretofore considered between pistons 35 and 36. Accordingly, the variable piston area factor will be considerably increased; and, by the inverse proportion, the regulated tension may be decreased in some 40 manner so that the proportion can prevail again to balance the piston structure. As presently described, such decrease in the regulated tension may result from various causes; but when once secured, the proportion 45 may be automatically maintained. Thus, so long as the piston areas acted upon by the regulated tension remain the same, the effective regulated tension may also remain substantially unchanged.

50 For another example, assume that the cylinders between pistons 34 and 35, and 35 and 36, be opened to atmosphere; and the cylinder above piston 36 be opened to regulated tension. Under these conditions, regulated 55 tension will act upwardly upon the piston 36 alone, with a considerably less pull than either of the other instances heretofore discussed, thereby decreasing the piston area factor of the proportion. Thereupon, the 60 regulated tension may be increased in some manner, in order to restore the balancing proportion which, when restored may be automatically maintained as described.

There are, of course, other permutations 65 and combinations of the piston areas which

may be utilized for varying this variable factor of the proportion, as will be understood by those skilled in the art.

As described, the piston area factor of the proportion may be subject to definite control, as by means of a perforated music sheet. Whenever this factor is varied, an inversely proportionate variation may take place in the regulated tension; and such variation may result from a number of causes, such 70 that the piston structure and the piston valve 31 may or may not be moved to assist in the rebalancing to suit the changed conditions.

Normally some leakage of the atmosphere to the chest 12 and various parts communicating therewith, may tend to reduce the regulated tension in said chest, whether or not any of the motor pneumatics F is in action. Any reduction in regulated tension from such cause may be compensated to a greater 80 or less extent by leakage between the high tension chest 14 and the chest 12, as by leakage past the piston valve 31. If, however, the regulated tension falls so low as to disturb the prevailing balancing proportion 85 90 there may result a downward movement of the piston structure, enlarging the openings between the chests 12 and 14 enough to permit high tension to restore more or less the regulated tension in the chest 12. Such 95 action may take place so promptly and quickly that, in effect, it serves to maintain the regulated tension substantially constant, rather than to restore it.

Each motor pneumatic F when idle contains atmospheric pressure which, when the pneumatic is thrown into operation, is opened to the regulated tension, thereby 100 tending to reduce the latter. Obviously, if many motor pneumatics F act simultaneously there may be a considerable tendency 105 to reduction in the regulated tension. Ordinarily in the operation of the piano player the regulated tension may be subjected to frequent fluctuations by the operation of the 110 motor pneumatics. Whenever such fluctuation so reduces regulated tension that the balancing proportion is disturbed, the piston valve 31 may enlarge communication between the high tension chest 14 and the chest 12, so 115 as to restore in the latter the tension governed by the prevailing condition of the piston areas in the balancing proportion. As already suggested, this restoring action takes place so promptly and rapidly that it is 120 rather a maintaining action.

From the above it will appear that whatever draughts are made upon the regulated tension chest 12, from whatever cause, said tension may always be maintained by the 125 described balancing operation of the piston structure controlling communication between the regulated and high tension chests. Immediately, however, the variable piston area factor of the balancing proportion is 130

changed, a new proportion is set up and a change in the regulated tension is at once effected.

It will be noted that the regulating action of the piston structure may act merely to preserve the desired regulated tension in spite of any draughts made thereupon as for instance by the motor pneumatics. That is to say, the regulating does not necessarily result from varying communication between the high tension chest and the regulated tension chest. For instance, assume that the piston area factor of the proportion is so changed that it requires a considerable reduction in regulated tension in order to establish the balancing proportion. Such change in piston area may be accompanied by the action of a considerable number of motor pneumatics F, which in effect suffices to reduce the regulated tension so as to establish the balancing proportion. Under such circumstances the mechanism is changed from one proportion to another and the regulated tension is reduced to a lower working level without having any change made in the communication between the two chests 12 and 14. Thus, in greater or less degree, the mere utilization of regulated tension in the chest 12 may cooperate with the variations in the piston area factor of the proportion so that the control of communication between the chests exercised by the piston valve may be of supplemental and auxiliary effect.

Hereinbefore the regulating mechanism has been described. It remains to describe the manner in which the same may be governed, i. e., in the specific instance, the manner in which the variable piston area factor is varied.

Referring again to Fig. 1, the duct 40 connects the cylinder above the piston 36 with a valve chamber 49 which, as shown, is open to atmosphere. In said chamber is a valve 50, arranged for closing alternatively the port to atmosphere, and the opening from said chamber 49 through the duct 51 to the regulated tension chest 12. The valve 50 is controlled by a diaphragm over a chamber 54, which communicates with a duct 56. A two-way valve 58 controls a port from the duct 56 to atmosphere, and a second port from the duct 56 to a chamber 59 communicating by a duct 60 with the high tension chest 14. The valve 58 is controlled by a diaphragm over a chamber 62, which communicates by a duct 63 with a valve box 64. The latter communicates by a duct 66 with a vent 67 in the tracker G. In the box 64 are two valves, 69, 70; the former controlling communication between the box 64 and a duct 72 leading to the duct 56; and the valve 70 controls communication from the box 64 through a duct 74 to the high tension chest 14. The valve 70 is controlled by a diaphragm over a chamber 76, the latter com-

municating with a duct 78 leading to a tracker vent 79.

When the tracker vent 79 is open, atmosphere is admitted to the duct 78 and the diaphragm chamber 76, thereby distending the diaphragm and elevating the valve 70. When the tracker vent 79 is closed, the bleeder vent 80, communicating with the duct 74 and high tension chest 14, exhausts from the duct 78 and diaphragm chamber 76.

The tracker vents 67 and 79 may be opened and closed by a moving perforated sheet in the usual manner. The positions shown prevail when the vent 79 is open and the vent 67 closed. Thus atmosphere is admitted to the vent 78 and diaphragm chamber 76, distending the diaphragm of the latter and elevating the valve 70. This closes the valve 69 and also opens communication from the diaphragm chamber 62 under the valve 58, through duct 63, valve box 64, and duct 74, to the high tension chest 14. Thereby the diaphragm of chamber 62 is balanced, permitting the valve 58 to close the outlet to atmosphere of the duct 56 and to place the latter in communication through the chamber 59 with the duct 60 and high tension chest 14. This exhausts from the diaphragm chamber 54 under the valve 50 and permits the latter to drop, opening the duct 40 to atmosphere, and closing communication from the regulated tension 12 through the duct 51 with the duct 40. Under these conditions there is high tension in duct 74, valve box 64, duct 63, and diaphragm chamber 62; and also in duct 60, chamber 59, ducts 56 and 72, and diaphragm chamber 54. There is atmosphere in diaphragm chamber 76 and in duct 40.

The conditions just described and shown at V in Fig. 1, may prevail only momentarily since the tracker vent 79 is preferably controlled by short perforations in the sheet so that the vent is open for periods of short duration only.

When the tracker vent 79 is closed with the parts in the positions just described, atmosphere will be drawn through the bleeding vent 80, exhausting from the diaphragm chamber 76, and permitting the valve 70 to descend, thereby closing communication between the duct 74 and the valve box 64. At the same time the valve 69 will be permitted to drop by gravity, since there is high tension on both sides thereof, to wit, in the valve box 64 and duct 72. The condition of the apparatus then prevailing is illustrated at V' in Fig. 1, in which high tension is still maintained in the diaphragm chamber 62', which communicates through duct 63' with the duct 72' (past the valve 69'), through the duct 60', with the high tension chest 14. This maintains the valve 58' closed and thereby continues the exhaust from diaphragm chamber 54' through

ducts 56' and 60', thereby maintaining the valve 50' in the position shown with the regulator duct 42 open to atmosphere. The valve mechanism on the right of Fig. 1 at 5 V may be identical with that at V', each set of mechanism being connected with the trackerboard by two appropriate ducts. The set V' has ducts 78' and 66', corresponding respectively to the ducts 78 and 66 10 of the set V. In the conditions shown the tracker vents 80 and 81 of the ducts 78' and 66' respectively are both closed.

If now the duct 66' be open, atmosphere will be admitted to the valve box 64'. This 15 will close the valve 69' and distend the diaphragm over the chamber 62', thereby elevating the valve 58'. Thus atmosphere is admitted past the valve 58' to the diaphragm chamber 54', thereby elevating the valve 50' 20 and opening communication between the duct 42 and duct 51' leading to the regulated tension chest 12.

Such a condition of a valve mechanism is illustrated at V² in Fig. 1, in which the 25 valve 69² is closed and the valve 58² is open, admitting atmosphere to the diaphragm chamber 54², thereby elevating the valve 50² and opening communication between the duct 41 and duct 51² leading to 30 the regulated tension chest.

The valve 69² may occupy its closed position shown at V², only momentarily; for as soon as the valve 58² is opened atmosphere is admitted to the upper side of the valve 69², 35 and thereby the latter is balanced and permitted to drop by gravity to the position of the valve 69' and V'. Thus atmosphere is present in the valve box 64² and chamber 62² and also in the duct 56² and diaphragm 40 chamber 54²; and none of said chambers and ducts is open to either tension chest. This condition will be in no wise changed if the duct 66² be closed, once having been opened to admit atmosphere.

45 In other words, once communication is opened between regulated tension and one of the cylinder ducts 40, 41 or 42 this communication may be maintained continuously until positively and intentionally interrupted by the opening of a duct 78, 78', or 78². In effect, by opening one of the ducts 66, 66' or 66² a valve mechanism is caused to 50 open communication between a cylinder duct and regulated tension, and is locked in position to maintain such communication. Accordingly, after opening one of said ducts 66, 66' or 66² the same may be closed at once, if desired, and all notes played subsequently to the opening thereof, will be 55 influenced by the regulation controlled thereby, until that regulation is interrupted by opening the appropriate duct 78, 78' or 78². Thus a sustained effect may be produced by having the ducts 66, 66' and 66² each 60 controlled by short perforations in a sheet 65

which may be just long enough to provide for the initial action of the valve mechanism, whereupon the latter may be locked in its new position.

Any one, or any permutation, of the ducts 70 66, 66' and 66² may be open at the same time, thereby controlling the pistons 34, 35 and 36, singly or permutatively.

With the valve mechanism in the condition shown at V² (except that the valve 69² 75 may have dropped), the duct 66² being closed, if the duct 78² be opened, atmosphere will be admitted to the diaphragm chamber 76², thereby opening valve 70², closing valve 69² and permitting the diaphragm chamber 80 62² to be exhausted through valve box 64² and duct 74². Thereupon the valve 58² closes the duct 56² from the atmosphere and permits the same and the diaphragm chamber 54² to be exhausted through the duct 60². 85 This causes the valve 50² to descend, thereby opening to atmosphere the cylinder duct 41. The parts as thus described occupy the positions shown at V in Fig. 1. As soon however, as the vent 83 is closed (and preferably as already described it is open only momentarily) the parts assume the positions shown at V'.

It will be noted that the various diaphragm chambers are preferably exhausted 95 through ducts 60, 74, communicating with the high tension chest, so that high tension is available to exhaust rapidly and promptly when desired. This is especially desirable (though not indispensable) in exhausting 100 from, for instance, the diaphragm chamber 54², since this can be accomplished rapidly under the influence of high tension, in opposition to regulated tension acting upon the upper side of the diaphragm of said chamber, thereby permitting a quick decisive closing action of the valve 50² to open the cylinder duct 41 to atmosphere, with minimum leakage from the regulated tension chest. 105

110 From the above it will be clear that opening any one or more of the tracker ducts 67, 82 or 81, will open the corresponding ducts 66, 66², or 66', thereby opening to regulated tension the appropriate parts of the regulating cylinder. One or more of the tracker vents 67, 82 or 81 being closed, the opening of the corresponding vent 79, 83 or 80 will have the contrary effect of interrupting communication between the appropriate cylinder part and regulated tension. 115

The manner in which the tracker vents just referred to are controlled, preferably by a perforated sheet, will be next described. Referring now to Fig. 2, it is assumed that 120 the note sheet there shown is moving in the direction of the arrow. At the right of the note sheet are a number of perforations arranged along lines of which those on line 79' register with the vent 79 of Fig. 1; those on 130

line 67' register with the vent 67; those on the line 83' register with the vent 83 and so on. The other perforations of the note sheet are intended to register with the vents of the tracker G, which lead to the motor pneumatics F.

The tracker G is shown by dotted lines in Fig. 2, with vents 79 and 82 open through perforations in the sheet. This places valve mechanisms V and V² in the conditions shown in Fig. 1, the former being what may be called "inactive" and the latter being "active" to admit regulated tension between pistons 35 and 36 of the regulator cylinder. A preceding perforation 80² had previously rendered valve mechanism V¹ idle, giving it the condition shown in Fig. 1.

Starting therefore with the same conditions shown in Fig. 1, brought about by the perforations 79², 82² and 80²—further travel of the sheet brings perforations 67² and 81² into registry with the tracker.

The perforation 67² negatives the previous effect of the perforations 79² and renders the valve mechanism V active to admit regulated tension above the piston 36. In like manner, the perforation 81² renders the valve mechanism V' active to admit regulated tension between the pistons 34 and 35. Thus all of the valve mechanisms are active; and regulated tension is present throughout the parts of the regulating cylinder. Under these circumstances the piston area factor of the proportion hereinbefore referred to, has (in the specific construction) its maximum value and therefore, by the inverse proportion, the regulated tension has its lowest value. Thus the note n² following the perforations 67² and 81² will be played with the lowest intensity which for convenience may be called the "first intensity."

In further movement of the perforated sheet a perforation 79³ registers with the tracker and changes the valve mechanism V to the inactive position shown in Fig. 1, wherein atmosphere is admitted above the piston 36. Under these conditions regulated tension prevails between pistons 34 and 35, and 35 and 36. Thus the piston area factor of the proportion is reduced by the area of the piston 36; and the regulated tension is correspondingly increased, the increase, in the specific instance, bringing the regulated tension to the next higher level. Thus a note controlled by the perforation n³ following the perforation 79³ will be played at the next higher intensity, which may be called the "second intensity."

In further movement of the sheet perforations 67³ and 83³ register with the tracker board. The perforation 67³ changes the valve mechanism V to active condition, admitting regulated tension above the piston 36; and the perforation 83³ renders the valve mechanism V² inactive, admitting atmos-

sphere between the pistons 35 and 36. Under these conditions the piston area variable factor of the proportion is further reduced; and regulated tension proportionately increased to a second higher level. Accordingly, a note controlled by a perforation n⁴ following the perforations 67³ and 83³ will be played with the third intensity.

Further travel of the perforated sheet brings a perforation 79⁴ into register with the tracker. This renders the valve mechanism V inactive, admitting atmosphere above the piston 36. Thus regulated tension is present only between pistons 34 and 35; and the piston area variable in the proportion is further reduced, and the regulated tension increased to its third higher level. The note controlled by the perforation n⁵ will therefore be sounded with the fourth intensity.

In further movement of the sheet, perforations 67⁴, 82⁴ and 80⁴ register with the tracker. The perforations 67⁴ changes the valve mechanism V to active condition, admitting regulated tension above the piston 36. The perforation 82⁴ changes the valve mechanism V² to active condition, admitting regulated tension between the pistons 35 and 36. The perforation 80⁴ renders the valve mechanism V' inactive, admitting atmosphere between the piston 34 and 35. Thus the piston area variable factor of the proportion is further reduced; and regulated tension is correspondingly increased to its fourth higher level. Thus the note controlled by perforation n⁶ will be played with the fifth intensity.

A perforation 79⁵ next registers with the tracker and renders the valve mechanism V inactive, admitting atmosphere above the piston 36; regulated tension prevailing then between pistons 35 and 36 only, and the regulated tension being at its fifth higher level, so that the note controlled by perforation n⁷ is played with the sixth intensity.

Perforations 67⁵ and 83⁵ follow next, the former rendering the valve mechanism V inactive, to admit regulated tension above the piston 36. The perforation 83⁵ renders the valve mechanism V² inactive. Thus the piston area variable factor of the proportion is reduced to the area of the piston 36; and, correspondingly, the regulated tension is increased to its sixth higher level, and the note controlled by perforation n⁸ is played with the seventh intensity.

A perforation 79⁶ next follows, rendering the valve mechanism V inactive and admitting atmosphere above the piston 36. Thus atmosphere is present throughout the regulating cylinder; and the piston area variable factor of the proportion is reduced substantially to zero, and regulated tension is increased to its highest level, which may be substantially that of high tension. Accord-

ingly, the note governed by perforation n^9 will be sounded with the highest or normal intensity, prevailing when the entire expression mechanism is idle.

5 It will be observed that the notes represented by perforations n^2 to n^9 inclusive, constitute a crescendo, each note being sounded with one of the graded intensities provided in the specific illustrative mechanism. The 10 preceding explanation is illustrative only, being designed merely to exemplify the operation of the specific apparatus shown in the drawing. It is to be understood of course that the parts may be varied in number, and proportioned in any practicable manner, as will appear to those skilled in the art.

As in the described crescendo of notes n^2 to n^9 inclusive, the natural sequence of tones 20 demanded by a composition being played, may prescribe such relative positioning of the note perforations that, as shown, the intensity perforations 67^2 , 81^2 , 79^3 , etc., may be readily located to give the desired effects, 25 by merely placing each such perforation in position to change the regulated tension at or before the instant that the appropriate tone is to be sounded.

When, however, a group of notes is intended to be played substantially simultaneously, it may be desired to play certain notes of the group louder than the others; and this may be readily effected, for instance by arranging the perforations for the louder 35 note or notes in advance of those for the softer notes; and placing an intensity reducing perforation in the rear of the louder-note perforations, and in position to control the softer-notes.

40 For example, referring to Fig. 2, the perforation p may be for a theme note; and p' for an accompaniment note therefor. In order to emphasize the theme note so that it shall be more prominent than the accompaniment, intensity perforations p^2 and p^3 45 may reduce the intensity of the note played by the accompaniment perforation p' , the theme perforation p being moved forward on the sheet so that it shall be beyond the effect of the intensity reducing perforations p^2 and p^3 . Likewise the perforations p^6 , p^7 and p^8 50 may play a chord with perforation p^9 , the latter being moved forward so as to be beyond the influence of the intensity reducing perforation p^{10} which is in alignment with perforations p^6 , p^7 and p^8 and which effects a differentiation between the tone of perforation p^9 and the remainder of the chord, by subduing the latter without in any 55 sense affecting the former.

60 Thus in all cases requiring a displacement of note perforations from their natural relations, those for the louder notes are advanced beyond the others, and the latter are placed properly in relation to the intensity reduc-

ing perforations to reduce the intensity of notes played thereby.

The preceding description will suffice to explain, for purposes of illustration, one of the various embodiments of which the invention is susceptible; but it is to be understood of course that the invention is by no means essentially limited to the specific construction, organization, and mode of operation described. Also, it is not indispensable 75 that all of the features of the invention be used conjointly, since they may be used separately to advantage.

I believe myself to be the first to invent governing means for automatic musical instruments comprising a fluid-balanced or completely fluid-controlled regulating device, such as is exemplified, in one specific construction and use, by the piston structure and cylinders hereinbefore referred to. As 80 regards features of the invention pertaining to a fluid balanced regulating member, and as regards other features which will appear to those familiar with the art, I believe myself entitled to be considered a pioneer. 90

Claims:

1. In an automatic musical instrument, the combination of playing-pneumatics for the individual notes to be sounded; a regulated-wind container; means for connecting 95 said container to playing-pneumatics for causing operation of the latter; a wind-supply container; means for connecting the latter with said regulated-wind container; governing means free from active mechanical restraint and situated intermediate the regulated-wind container and the wind-supply container, to govern communication therebetween; and means to operate pneumatically said governing means. 100

2. In an automatic musical instrument, the combination of playing-pneumatics for the individual notes to be sounded; a regulated-wind container; means for connecting said container to playing-pneumatics for causing 110 operation of the latter; a wind-supply container; means for connecting the latter with said regulated-wind container; a regulating valve mechanism intermediate the regulated-wind container and the wind-supply 115 container, including a unitary valve-governing number having an area subjected to pneumatic pressure for governing said valve; and means to vary the extent of said area subjected to said pneumatic pressure. 120

3. In an automatic musical instrument, the combination of playing-pneumatics for the individual notes to be sounded; a regulated-wind container; means for connecting said container to playing-pneumatics for causing 125 operation of the latter; a wind-supply container; means for connecting the latter with said regulated-wind container; a regulating valve mechanism intermediate the regulated-wind container and the wind-supply 130

5 container, including a governing device having an area subjected to pneumatic pressure from said regulated-wind container; and means to vary the extent of said area subjected to said pneumatic pressure.

4. In an automatic musical instrument, the combination of playing-pneumatics for the individual notes to be sounded; a regulated-wind container; means for connecting said container to playing-pneumatics for causing 10 operation of the latter; a wind-supply container; means for connecting the latter with said regulated-wind container; a throttle valve intermediate said containers to govern 15 communication therebetween; and unitary valve governing means connected to said throttle valve and having an area arranged to be subjected to pneumatic pressure; and means for varying the extent of said area subjected to pneumatic pressure.

5. In an automatic musical instrument, the combination of playing-pneumatics for the individual notes to be sounded; a regulated-wind container; means for connecting said 20 container to playing-pneumatics for causing the operation of the latter; a wind-supply container; means for connecting the latter with said regulated-wind container; and a throttle valve mechanism intermediate said 25 containers to govern communication therebetween, suspended therebetween exclusively by opposed pneumatic pressures.

6. In an automatic musical instrument, the combination of playing-pneumatics for the 30 individual notes to be sounded; a regulated-wind container; means for connecting said container to playing-pneumatics for causing operation of the latter; a wind-supply container; means for connecting the latter with said regulated-wind container; and a throttle valve mechanism intermediate said 35 containers to govern communication therebetween, merely suspended therebetween, and free from active mechanical restraint, by 40 opposed pneumatic pressures.

7. In an automatic musical instrument, the combination of playing-pneumatics for the individual notes to be sounded; a regulated-wind container; means for connecting said 50 container to playing-pneumatics for causing operation of the latter; a wind-supply container; means for connecting the latter with said regulated-wind container; a throttle valve mechanism intermediate said 55 containers to govern communication therebetween, suspended therebetween exclusively by opposed pneumatic pressures; and means to vary pneumatic action of one of said pneumatic pressures on said valve mechanism.

60 8. In an automatic musical instrument, the combination of playing-pneumatics for the individual notes to be sounded; a regulated-wind container; means for connecting said container to playing-pneumatics for causing 65 operation of the latter; a wind-supply con-

tainer; means for connecting the latter with said regulated-wind container; a throttle valve intermediate said containers to govern communication therebetween; and valve governing means connected to said throttle valve, presenting an area arranged to receive pneumatic pressure; and controlling means to introduce pneumatic pressure from the regulated-wind container to different extents of said area.

70 9. In an automatic musical instrument, the combination of playing-pneumatics for the individual notes to be sounded; a regulated-wind container; means for connecting said container to playing-pneumatics for causing 80 operation of the latter; a wind-supply container; means for connecting the latter with said regulated-wind container; a throttle valve intermediate said containers to govern communication therebetween; valve governing means connected to said throttle valve, presenting an area arranged to receive pneumatic pressure; controlling means to introduce pneumatic pressure from the regulated-wind container to different extents of 85 said area; a tracker; and means operated from the tracker to govern said controlling means.

90 10. In an automatic musical instrument, the combination of playing-pneumatics for the individual notes to be sounded; a regulated-wind container; means for connecting said container to playing-pneumatics for causing 95 operation of the latter; a wind-supply container; means for connecting the latter with said regulated-wind container; a throttle valve intermediate said containers to govern communication therebetween; and a valve governing member connected to said 100 throttle valve, and having an area arranged to be subjected to pneumatic pressure; and means for applying pneumatic pressure selectively to fractional parts of said area to 105 variably govern communication between the two containers.

11. A tone-governing apparatus for automatic musical instruments, the same comprising the combination of expression-regulating means to govern a plurality of grades of tone intensities; and governing means 115 therefor free from active mechanical restraint for causing any such grade to be maintained as desired.

12. A tone-governing apparatus for automatic musical instruments, the same comprising automatically variable, expression-regulating means free from active mechanical restraint to govern a plurality of grades of tone intensity.

125 13. A tone-governing apparatus for automatic musical instruments, the same comprising the combination of automatically variable expression-regulating means to govern a plurality of grades of tone intensity; and means free from active mechanical re- 130

straint for causing the same to maintain any intensity grade, as desired.

14. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; automatic means acted upon by regulated wind to govern said throttle valve; and means for varying the effectiveness of regulated wind on said automatic means, to vary the action of the throttle valve.

15. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a valve intermediate said containers to govern communication therebetween; and valve governing means presenting a plurality of separately exposed areas; and selective means for opening said areas selectively to regulated wind.

16. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; valve means for governing communication between said containers; and unitary valve governing means presenting a plurality of separately exposed areas; and means for applying pneumatic pressure to said areas singly or permutatively.

17. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; valve means for governing communication between said containers; and valve governing means presenting a plurality of separately exposed areas; and means for applying regulated wind to said areas singly or permutatively.

18. In an automatic musical instrument, the combination of playing-pneumatics for the individual notes to be sounded; a regulated-wind container; means for connecting said container to playing pneumatics for causing operation of the latter; a wind-sup-

ply container; means for connecting the latter with said regulated-wind container; valve means for controlling communication between said containers; a movable valve-governing means connected to said valve and arranged to be acted upon by regulated wind; and means for variably connecting said valve governing means with regulated wind.

19. A tone-governing apparatus for automatic musical instruments, the same comprising the combination of a regulated-wind container; means providing a plurality of areas arranged to be exposed to regulated wind; means for subjecting said areas permutatively to regulated wind; a tracker; and tracker controlled governing means for said last named means.

20. In an automatic musical instrument, the combination of playing-pneumatics for the individual notes to be sounded; a regulated-wind container; means for connecting said container to playing-pneumatics for the cause of operation of the latter; a wind-supply container; means for connecting the latter with said regulated-wind container; a throttle valve intermediate said containers to govern communication therebetween; valve governing means connected to said throttle valve and governed by opposed forces including the pneumatic pressure of regulated-wind acting upon an area of said valve governing means, whereby the regulated-wind pressure multiplied by the area acted upon thereby tends to equal and balance the forces opposed thereto; and means for disturbing said balance by varying one of said areas.

21. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; valve governing means connected to said throttle valve and presenting acting areas to opposed pneumatic forces including the pneumatic pressure of regulated-wind, whereby the regulated-wind pressure multiplied by the area acted upon thereby equals and balances the opposed pneumatic pressure multiplied by the area acted upon thereby; and means for disturbing said balance by varying one of said areas.

22. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a

throttle valve intermediate said containers to govern communication therebetween; valve governing means connected to said throttle valve and presenting acting areas to opposed pneumatic forces including the pneumatic pressure of regulated-wind, whereby the regulated-wind-pressure multiplied by the area acted upon thereby equals and balances the opposed pneumatic pressure multiplied by the area acted upon thereby; and means for disturbing said balance by varying either of said areas.

23. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; valve governing means connected to said throttle valve and presenting acting areas to opposed pneumatic forces including the pneumatic pressure of regulated-wind, whereby the regulated wind pressure multiplied by the area acted upon thereby equals and balances the opposed pneumatic pressure multiplied by the area acted upon thereby; and means for disturbing said balance by varying both of said areas.

24. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; valve governing means connected to said valve and having an area to be acted upon by pneumatic pressure; and means for admitting atmosphere and regulated-wind alternatively to said area.

25. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; valve governing means connected to said valve and having a plurality of areas to be acted upon by pneumatic pressure; and means for admitting atmosphere and regulated-wind alternatively to said areas respectively.

26. In an automatic musical instrument, the combination of playing-pneumatics for

the individual notes to be sounded; a regulated-wind container; means for connecting said containers to playing pneumatics for causing operation of the latter; a wind-supply container; means for connecting the latter with said regulated-wind container; a throttle valve intermediate said containers to govern communication therebetween; valve governing means connected to said valve and having a plurality of areas to be acted upon by pneumatic pressure; and means for admitting atmosphere to certain of said areas and regulated-wind to other said areas.

27. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; unitary valve governing means connected to said throttle valve and having an area arranged to be subjected to pneumatic pressure; and a plurality of valve mechanisms separately operable for applying pneumatic pressures to different fractional parts of said area.

28. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; valve means to govern communication between said containers; valve governing means connected to said valve means and comprising a piston; and means for applying different pneumatic pressures to opposite sides of said piston to control the latter by the differential pressure.

29. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; valve means to govern communication between said containers; and valve governing means comprising a piston structure having thereon pistons of different areas.

30. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; valve means to govern communication between said containers; and valve governing means comprising a piston structure having thereon pistons of different areas.

latter with said regulated-wind container; valve means to govern communication between said containers; valve governing means comprising a part movable by the differential of pneumatic pressures thereon; and means to introduce atmosphere and regulated pressure in different proportions thereto to vary said differential.

31. In an automatic musical instrument, 10 the combination of playing-pneumatics for the individual notes to be sounded; a regulated-wind container; means for connecting said container to playing-pneumatics for causing operation of the latter; a wind-supply container; means for connecting the latter with said regulated-wind container; valve means to govern communication between said containers; valve governing means having an area to be subjected to 15 regulated-wind; a tracker; means operated from one tracker vent to admit regulated-wind to said valve governing means, and operated by another tracker vent to cut off regulated-wind therefrom.

25. 32. A tone-governing apparatus for automatic musical instruments comprising, in combination, a regulating-valve; a plurality of pistons to govern the same; and cylinder means for the pistons.

30. 33. A tone-governing apparatus for automatic musical instruments comprising, in combination, a regulating-valve; a plurality of connected pistons to govern the same; and cylinder means therefor.

35. 34. A tone-governing apparatus for automatic musical instruments comprising, in combination, a regulating-valve; a plurality of pistons, having a common stem, to govern the valve; and cylinder means therefor.

40. 35. A tone-governing apparatus for automatic musical instruments comprising a regulating piston-valve; a plurality of pistons for governing the same; a common stem for the valve and said pistons; and cylinder means for the latter.

50. 36. A tone-governing apparatus for automatic musical instruments, comprising, in combination, containers for high and regulated tensions respectively; regulating means for varying the tension in the regulated tension container; and controlling means exposed to and operated by high tension for introducing regulated tension to said regulating means.

55. 37. In an automatic musical instrument, the combination of playing-pneumatics for the individual notes to be sounded; a regulated-wind container; means for connecting said container to playing-pneumatics for causing operation of the latter; a wind-supply container; means for connecting the latter with said regulated-wind container; a throttle valve intermediate said containers to govern communication therebetween; 60 valve governing means connected to said

valve and having an area to be acted upon by pneumatic pressure; and means for admitting atmosphere and regulated-wind to act in opposition to the pneumatic pressure acting upon said area.

38. In an automatic musical instrument the combination of playing pneumatics; a main source of power for operating the playing pneumatics; a throttle valve intermediate the main source of power and 75 the playing pneumatics; valve governing means controlled by opposed forces including the pneumatic pressure of regulated air upon a variable acting area exposed thereto, whereby the regulated air 80 pressure multiplied by the area acted upon tends to close said valve and equals and balances the opposing force which tends to open said valve; and means for disturbing said balance by varying the area 85 acted upon by regulated air pressure.

39. In an automatic musical instrument the combination of playing pneumatics; a main source of power for operating the playing pneumatics; a throttle valve intermediate said source of power and 90 said playing pneumatics; valve governing means connected to said valve including means providing a force tending to open said valve and an area to be acted upon 95 by regulated pneumatic pressure to tend to close said valve; and means for admitting atmosphere and regulated air to different parts of said area to vary the force tending to close said valve.

40. An instrument of the character described comprising, in combination, playing pneumatics; a main source of power for operating said playing pneumatics; a throttle valve interposed between said 105 source of power and the playing pneumatics; a plurality of independently operable regulating means connected to said throttle valve and adapted each to establish a different degree of regulation in the 110 power applied to said playing pneumatics; and means to connect said regulating means with regulated tension.

41. An instrument of the character described comprising, in combination, playing pneumatics; a main source of power for operating said playing pneumatics; a throttle valve interposed between said source of power and the playing pneumatics; and a plurality of independently 115 operable regulating means connected to said throttle valve; and means to introduce regulated air pressure to said regulating means selectively or in combination.

42. In a musical instrument the combination of playing pneumatics; a main source of power for operating said playing pneumatics; a throttle valve intermediate said main source of power and the playing pneumatics to govern communica- 125 130

tion therebetween; valve governing means connected to said throttle valve; and a plurality of individual regulating means having connection with regulated tension for controlling said valve governing means to initiate respectively different degrees of of playing intensity.

43. In an automatic musical instrument, the combination of playing pneumatics; a 10 main source of power for operating the playing pneumatics; and pneumatically operated means free from active mechanical restraint and interposed between the main source of power and the playing 15 pneumatics to maintain uniformity of playing intensity at any desired level.

44. In a pneumatic tension graduating device, the combination of a pneumatic, a tension graduating valve controlled thereby, 20 an auxiliary pneumatic connected with the first named pneumatic directly for assisting its collapse, and means for connecting the auxiliary pneumatic with a source of air tension to set it into operation.

45. In a musical instrument, the combination with a tube for conducting air from an action, a main wind-way, and means for conducting air from one to the other, of a 30 pneumatic, means for conducting the air to the pneumatic for the purpose of reducing the air tension on the action, a second pneumatic, the movable leaf of which is fixed to the movable leaf of the first pneumatic, and means for connecting the second pneumatic 35 with a source of air tension for the purpose of causing it to collapse in unison with the first pneumatic and increasing the reduction of tension.

46. In a self-playing musical instrument, 40 an expression-governing device having a tension controller normally set to produce a certain tone effect, and means for subduing the tone including separate pneumatic assisters for exerting closing force upon the 45 controller to reduce the air tension and means for energizing said assisters one by one in sequence.

47. In a self-playing musical instrument, 50 an expression-governing device including a pneumatic having yielding means for opening it with a force substantially equal to that of the air tension therein necessary to produce a certain tone effect, and pneumatic means for exerting a closing effect upon the 55 first-named pneumatic against the action of said opening means.

48. In a self-playing musical instrument, 60 an expression-governing device including a pneumatic, yielding means for opening said pneumatic under a predetermined force sufficient to cause the production of loud tone effects, a pneumatic assister for exerting closing pressure upon the first-named pneumatic against the action of the opening 65 means to cause the production of softer tone

effects, and means for energizing said pneumatic assister.

49. In a self-playing musical instrument, 70 an expression-governing device including a pneumatic and yielding means for holding said pneumatic open under a predetermined force, in combination with an auxiliary pneumatic acting upon the first-named pneumatic in opposition to its opening means, an atmosphere port communicating 75 with the auxiliary pneumatic, an exhaust port, and means for alternately placing the atmosphere port in communication with the exhaust port and with the atmosphere to cause the operation of the auxiliary pneumatic.

50. In a self-playing musical instrument, 80 an expression-governing device including a pneumatic and means for opening the same under a force sufficient to cause the instrument to play with a certain tone effect, in combination with an auxiliary pneumatic acting upon the first-named pneumatic in opposition to said opening means, an exhaust chamber, and means for placing the 85 auxiliary pneumatic in communication with the exhaust chamber.

51. In a self-playing musical instrument, 90 an expression-governing device including a pneumatic, and means for opening the same under a force sufficient to cause the instrument to play with a certain tone effect, in combination with an auxiliary pneumatic acting upon the first-named pneumatic in opposition to said opening means, an exhaust chamber, and means for alternately placing said auxiliary pneumatic in communication with the exhaust chamber and with the atmosphere.

52. In a self-playing musical instrument, 100 an expression-governing device including a pneumatic and means for opening the same under a force sufficient to cause the instrument to operate with a certain tone effect, in combination with an auxiliary pneumatic 110 acting upon the first-named pneumatic in opposition to said opening means and normally in communication with the atmosphere, an exhaust chamber, and means for cutting off communication between the auxiliary pneumatic and atmosphere and placing it in communication with the exhaust chamber.

53. In a pneumatic tension graduating device, the combination of a pneumatic, a tension graduating valve controlled thereby, an auxiliary pneumatic connected with the first named pneumatic for assisting its collapse, and means for connecting said auxiliary pneumatic with the interior of the first 120 named pneumatic to assist its operation.

54. In a pneumatic tension graduating device, the combination of a pneumatic, a tension graduating valve controlled thereby, a plurality of auxiliary pneumatics connected 125 130

with the first named pneumatic for assisting its collapse, and means for connecting the auxiliary pneumatics successively in sequence with a source of air tension to set them into operation.

55. In a pneumatic tension graduating device, the combination of a pneumatic, a tension graduating valve controlled thereby, a plurality of auxiliary pneumatics connected 10 with the first named pneumatic for assisting its collapse, and means for connecting the auxiliary pneumatics successively in predetermined sequence with a source of air tension to set them into operation.

56. The combination with a main wind-way, means for conducting air from an action to the wind-way, and a valve for choking the tension, of a pneumatic adapted to be connected with said means and adapted 20 to be collapsed when connected therewith, the movable member of which constitutes means for moving said valve into its choking position, a second pneumatic, the movable member of which is fixed with respect to the 25 first named movable member, and means whereby the second pneumatic can be connected with a source of air tension, whereby both pneumatics will operate together and still further close said valve.

57. In a self-playing musical instrument, an expression-governing device including a pneumatic, means for opening said pneumatic with a predetermined force sufficient to cause the production of loud tone effects, 30 an auxiliary pneumatic connected to and co-acting with the movable side of the first-named pneumatic against the action of said opening means to cause the production of softer tone effects, an exhaust chamber, and 35 means for opening and closing communication between the exhaust chamber and said auxiliary pneumatic.

58. A tone-governing apparatus for automatic musical instruments comprising, in 40 combination, a regulating valve; a plurality of chambers each having a fixed wall and a 45

movable wall, said movable walls being connected to a common valve stem to govern said valve; and means to connect said chambers with regulated wind and atmosphere. 50

59. Controlling mechanism for a pneumatically operated musical instrument comprising, in combination, a pneumatic regulating device and means to admit thereto regulated air and atmosphere in varying relations. 55

60. Controlling mechanism for a pneumatically operated musical instrument comprising, in combination, a pneumatic regulating device, means to admit a maximum of 60 regulated air thereto for a certain effect and means to admit atmosphere thereto for a different effect.

61. Controlling mechanism for a pneumatically operated musical instrument comprising, in combination, a pneumatic regulating device, means to admit a maximum of 65 regulated air thereto to produce soft tone effects and means to admit atmosphere thereto to produce louder tone effects. 70

62. Controlling mechanism for a pneumatically operated musical instrument comprising, in combination, a pneumatic regulating device, means to admit regulated air thereto and means to admit atmosphere with 75 an effect progressively lessening the effect of regulated air.

63. Expression controlling mechanism for a pneumatically operated musical instrument comprising, in combination, a regulating device, means to control the admission of 80 regulated air and atmosphere thereto in different relations, each change in said relations producing an incremental expression change. 85

In testimony whereof, I have signed my name to this specification, in the presence of two subscribing witnesses.

CHARLES F. STODDARD.
